APPARATUS FOR HEAT SEALING IDENTIFICATION TAGS TO GARMENTS AND THE LIKE

Jamieson A. Filsinger and Philip N. Braun, Syracuse, N.Y.; said Jamieson A. Filsinger assignee to Philip N. Braun

Application May 28, 1956, Serial No. 587,582

4 Claims. (Cl. 216—29)

This invention relates to apparatus for heat sealing identification tags to garments and the like in connection with laundering and dry cleaning processes.

Machines of this type are employed for affixing identification labels to articles to be processed in laundries and dry cleaning establishments, the identification tag being provided on one side with thermoplastic adhesive material. These machines include a heater iron and a garment platen over which a part of the garment is draped, the platen being moved toward the heating iron. The tags are usually formed from a roll of tape or sheet material. Means is provided for positioning the free end portion of the tape in overlying relation to the heating iron and upon movement of the garment platen toward the iron, the end portion of the tape is severed to form the tag, and the tag is squeezed between the heater arm and the garment. The heat from the iron reactivates the adhesive and the simultaneous application of pressure seals the tag to the garment. These machines also include printing mechanism for printing the desired identifying indicia on the reverse side of the tag—that is, the side contacting the heater iron. A machine of this type is disclosed in its entirety in the copending application of Philip N. Braun, Serial Number 459,294, filed September 30, 1954, now Patent No. 2,825,480, issued on March 4, 1958.

This invention has to do particularly with the structure of the garment platen, and has as an object an arrangement wherein the tape severing shear is mounted in close proximity to the heater iron. The garment platen embodying a base portion and a movable garment contacting portion mounted thereon, the base and the movable element having means cooperable during the initial application of pressure by the platen against the garment and tag, while the latter is overlying the face of the heating iron, to effect a sidewise or lateral shifting of the platen, garment and tag, to move the tag in full registration with the face of the heating iron, whereby heat and pressure are applied to the tag over the entire area thereof.

The invention consists of the novel features and of the combinations and constructions hereinafter set forth and claimed.

In describing this invention, reference is had to the accompanying drawings in which like characters designate corresponding parts in all the views.

In the drawings—

Figure 1 is a side elevational view of that portion of the machine embodying the platen, platen carrying arm and heater iron.

Figure 2 is a top plan view illustrating the anvil moved forwardly toward the heater iron but spaced an appreciable distance therefrom.

Figure 3 is a view similar to Figure 2 with the movable element of the platen initially contacting the tag, the tag having at that instant been severed from the tape.

Figure 4 is a view similar to Figure 3, showing the position of the parts with the anvil under full pressure compressing the garment and tag against the heater iron.

2

Figure 5 is a view taken on a line corresponding to line 5—5, Figure 1.

Figure 6 is a front elevational view of the heating iron, tag positioning and tag severing mechanism.

5 The frame consists of a U-shaped member formed of sheet metal and having vertically extending side walls 10, 11, and a bottom wall 12. A shaft 13 is journaled in the side walls 10, 11, to provide a pivotal mounting for an arm 14 provided at its outer end with laterally 10 extending handle projections 15. The back wall 17 of the frame extends upwardly, and a heater iron 18 is secured thereto. The platen carrying arm 14, intermediate its ends, is formed with a forwardly projecting portion 20 carrying a transversely extending pin 21 which, 15 when the arm is moved toward the heater arm 18, passes over the hooked end 22 of a link 23 pivoted at 24 to a vertically disposed lever 25. A plate 26 is secured to the back wall 17 of the frame, and carries a bracket 27 to which the upper end of the lever 25 is pivotally 20 mounted, as by pin 28. The link 23 is supported intermediate its ends on a pin 29 mounted in the side walls 10, 11, and the link is formed with a downwardly curved cam surface 30. The link is urged downwardly on the pin 29 by a tension spring 32, see Figure 1. When the 25 arm 14 has been moved about its pivot 13 manually until the platen is in the position shown in Figure 2, the pin 21 is moved behind the hooked end 22 of link 23. Thereupon, the lever 25 is moved in a counter-clockwise direction, Figure 1, about its pivot 28 by power means, 30 such as a fluid actuated cylinder and piston structure, not shown, and through the instrumentality of the link 23 the platen, with the garment draped thereover, is drawn tightly against the identification tag, and the latter is pressed against the heating iron, whereby heat and pressure are applied to the tag to effect the sealing of the tag to the garment.

The identification tags are formed from a strip or tape of suitable material, the face side confronting the garment platen, being coated with a suitable thermoplastic adhesive. This tape is indicated at 35. The supply of tape being usually in roll form and the machine proper having a tape feeding mechanism operable to advance the tape a predetermined distance each time the platen is moved into engagement with the heating iron. A 40 form of tape feed is illustrated in the Braun application, 459,294, previously mentioned. A guide structure 33 is provided to guide the tape as it is advanced from the roll, and to position the end portion of the tape in overlying relation to the face of the heating iron 18, see Figures 2 and 6. A stationary shear blade 37 is fixed to the left hand end of the heater iron 18 and a movable shear blade 38 is mounted for cooperation with the stationary blade 37. The blade 38 is mounted on a pivot 45 and is maintained in tight shearing relation to the fixed blade 37 by a leaf spring 41 carried by the depending portion 42 of the fixed blade, see Figure 6.

The movable blade 38 has a rearwardly extending portion pivotally attached to the upper end of a vertically disposed link 43, see Figure 1. The lower end of the 50 link 43 is formed with an aperture 45, elongated in a direction lengthwise of the link, to receive a pin 46 carried on an arm 47 attached to the platen carrying arm 14. The arrangement is such that when the face of the platen initially contacts the tag 36, the movable shear 55 severs the end portion 36 to form the tag.

The garment supporting platen consists of a base 50 detachably secured to the arm 14, as by screws 51. The forward edge of the base 50 is formed with a relatively deep, rectangular shaped, slot 52 in which there is slidably mounted a garment supporting or contacting element. The inner portion 54 of this movable element is slidably mounted in slot 52 in the base 50. A bar 56

is mounted intermediate the inner end of the portion 54 and the bottom of the slot 52. A pin 57 is secured to the bar 56, intermediate the ends thereof, and is slidably mounted in a bore 58 formed in the base member 50. The bar 56 is yieldingly urged outwardly against the portion 54 by helical compression springs 59. Outward movement of the portion 54 is limited by a pin 60 extending through the slotted portion of the base and through an aperture 61 which is elongated in a diagonal direction, the slot 61 and pin 60 serving to cam the movable element to the left by action of springs 59, as shown in Figures 2 and 3.

The outer enlarged portion 64 of the movable element is also provided with a rectangular shaped slot extending lengthwise of the element, and in which is positioned a channel member 66. A pad 67 of resilient material, such as rubber, is mounted in the channel member 66, and is retained against the bottom wall 68 thereof, by a pin 69 which extends through the side walls of the channel member and the rubber pad, and also through the portion 64. The opposite end of the pad is retained by a pin 70 which extends through the side walls of the channel member, but does not extend through the side walls of the outer portion 64 of the movable member. An aperture is provided extending inwardly from the bottom wall of the slot in the portion 64, and a helical compression spring 71 is positioned in this bore and acts against the bottom wall 68 of the channel member. The spring 71 is positioned toward the pin 70 whereby the channel member is moved about its pivotal mounting 69, this movement being limited by a plate 74 having a hooked end portion 75 engaging the bottom wall 68 of the channel member, the plate 74 being secured to the portion 54 of the movable member as by screws 76.

With this arrangement, the movable member is normally positioned outwardly and shifted to the left, Figures 2 and 3, of the base 50. Also, the pad 67 is in canted position. The garment is draped over the pad 67, and the arm 14 is moved toward the heater iron during which movement the end portion 36 of the tape is advanced to overlying relation with the heater iron 18. As the forward corner of the canted pad 67 engages the end portion 36 of the tape, as shown in Figure 3, the shear blade 38 is actuated to sever the end portion from the tape to form the tag. This engagement of the tag prevents it from falling or moving out of place. Further movement of the platen toward the heating iron, under the influence of the power actuator referred to, effects movement of the pad 67 about the pivot 69 to bring the pad and channel member in parallel relation with the face surface of the iron 18 and thereupon, the movable element is moved inwardly of the base against compression springs 59 and during this inward movement, the movable element and the pad carried thereby are shifted laterally to the right, as shown in Figure 4, and this movement effects similar shifting of the severed tag, whereby the entire area of the reverse side of the tag is brought in registering contact with the face of the heater iron 18 and accordingly, heat and pressure are applied over the entire area of the tag during the sealing operation. This results in the tag being more uniformly affixed to the garment.

What we claim is:

1. Apparatus for heat sealing thermoplastic coated

identification tags to garments comprising a frame, a heater iron mounted in the frame and having a heating surface, means for positioning the free end portion of a tape from which the tags are formed in overlying relation to the heating surface of said iron, a garment platen, means operable to effect relative movement between said iron and platen to effect compression of a garment against the end portion of the tape and to press the latter against said heater iron, a shear mounted in juxtaposition to said iron and being operable upon such relative movement between the platen and iron to sever said end portion of the tape to provide the identification tag, said platen comprising a base, a garment engaging member mounted on said base for movement relative thereto and projecting therefrom toward said heater iron, and means responsive to the exertion of pressure against said severed tag for shifting said member and the severed tag laterally across the surface of the heater iron in a direction away from said shear.

2. Apparatus as defined in claim 1 and including means for yieldingly opposing such shifting movement of said garment engaging member.

3. Apparatus as defined in claim 1 wherein said base and said movable member have coacting means for guiding the shifting of said shiftable member under pressure between the platen and said heater iron.

4. Apparatus for heat sealing thermoplastic coated identification tags to garments comprising a frame, a heater iron mounted in the frame and having a heating surface, means for positioning the free end portion of a tape from which the tags are formed in overlying relation to the heating surface of said iron, a garment platen, means operable to effect relative movement between said iron and platen to effect compression of a garment against the end portion of the tape and to press the latter against said heater iron, a shear mounted in juxtaposition to said iron and being operable upon such relative movement between the platen and iron to sever said end portion of the tape to provide the identification tag, said platen comprising a base, a pad mounted on the base and extending in angular relation to the heating surface of said iron to cause the garment carried by said platen to engage the end of the tag remote from said shear, and said pad being movable on said base in parallel relation to the heating surface of said iron upon the exertion of pressure on said tag to shift said tag laterally along said iron.
